UNITED STATES PATENT OFFICE.

WILLIAM H. HULTGREN, OF CHICAGO, ILLINOIS, ASSIGNOR OF ONE-HALF TO
HERBERT A. BEIDLER, OF SAME PLACE.

SAFETY-VALVE FOR HYDRAULIC ELEVATORS.

SPECIFICATION forming part of Letters Patent No. 443,208, dated December 23, 1890.

Application filed July 6, 1889. Serial No. 316,708. (No model.)

To all whom it may concern:

Be it known that I, WILLIAM H. HULTGREN, of Chicago, in the county of Cook and State of Illinois, have invented certain new and useful Improvements in Safety-Valves for Hydraulic Elevators; and I do hereby declare that the following is a full, clear, and exact description thereof, reference being had to the accompanying drawings, and to the letters of reference marked thereon, which form a part of this specification.

This invention relates to hydraulic elevators, and more particularly to auxiliary or safety valves for automatically closing the water-passage leading from the main valve to the hydraulic cylinder when the elevator-cab, by accident or otherwise, reaches the extreme limit of its movement in either direction.

In the drawings, Figure 1 is a side elevation of an elevator-valve embodying my invention, the same being shown partly in section. Fig. 2 is a central vertical longitudinal sectional view of the auxiliary valve. Fig. 3 is a similar view of a modified form of valve embodying my invention.

As illustrated in the drawings, A is a main-valve cylinder, and B and C cylinders which form parts of devices for actuating or controlling the main valve, and which are herein denominated "controlling-cylinders." Said cylinders A, B, and C are located in alignment with each other and preferably made of the same diameter. The valve-cylinder A is provided with a central annular port *a*, communicating with the lateral discharge-passage A', which leads to the operating-cylinder of the elevator. Within the said cylinder A are located two pistons D D, arranged at a somewhat greater distance apart than the width of the port *a* and rigidly connected with each other. The said cylinder A and the piston together form the main controlling-valve by means of which the influx of water to an exit of water from the operating-cylinder is governed. The said cylinder A is constructed in a well-known manner with a lining or bushing A², affording bearing-surface for the pistons D D and provided with a plurality of parallel slots *a'* opening into the port *a*. The valve-cylinder A is opened at one end to the atmosphere, the end of the

cylinder being commonly connected with a discharge-pipe for the water flowing from the operating-cylinder. At its opposite end the said cylinder A opens into or communicates with an annular space or port *e*, located between the cylinder A and the cylinder B and communicating with the water-inlet passage E, Fig. 1, which is connected with a water-main or other pipe supplying water under pressure.

When the pistons D D are moved toward the discharge end of the cylinder A, water is admitted from the inlet-passage E through port *a* to the passage A', leading to the operating-cylinder, while by moving the said pistons in the opposite direction or away from the discharge end of the cylinder A communication between the passages E and A' is closed, and the said passage A' is brought into communication with the discharge end of the cylinder. By moving the said valve-pistons D D to the right or left, therefore, the flow of water to the controlling-cylinder and its exit therefrom may be controlled, as desired, while by placing the valve-pistons in an intermediate position communication with the operating-cylinder is entirely closed. The main valve is constructed and operates substantially in the same manner as similar valves heretofore employed for the same purpose.

Within the controlling-cylinders are located suitable controlling-valves, which are connected with the pistons D D by means of a piston-rod D'. F indicates the valve-chest of a pilot-valve. The said controlling-valves and pilot-valve are suitably connected with operating ropes or cables F' F', which extend upwardly through the elevator-shaft, and one of which passes through the elevator, so that it may be grasped and controlled by the operator to operate the said controlling and pilot valves, which in turn actuate the main valve of the elevator.

The apparatus above described does not form part of the invention claimed in this application, and the same is fully described and claimed in a separate application for Letters Patent, Serial No. 313,660, filed by me in the United States Patent Office June 10, 1889.

Between the lateral discharge-passage A' of

close the valve, and after the valve is closed the pistons will be left free to be moved backward a short distance, so as to partially open the valve, and thus allow a sufficient inflow 5 of water to start the piston of the hydraulic cylinder in its return movement.

The operation of the parts when the elevator is descending is just the reverse of that above described. In the descent of the elevator 10 the water flows upwardly through the valve-casing. The piston-rod I^4 moves to the right and causes the lug i^5 to strike the lever, which moves the piston-rod I^2 and pistons to the right through a distance less than their 15 full stroke. The force of the water in this case is exerted against the piston I' and moves the same into the valve-seat g' . In reversing the movement of the elevator after it has been stopped in this manner the pistons 20 will be free to move backwardly by the action of the water thereon until the lever strikes the lug i^5 , when the movement of the pistons will be temporarily arrested until the movement of the rod I^4 shifts the said lug i^5 backwardly a distance sufficient to allow the pistons to move the full length of their stroke. The movement of the pistons in both directions is limited by stops, which act to positively hold one or the other of the pistons in 25 the valve-seat g' . In the particular instance illustrated the inner surface of the head H^3 forms a stop for contact with the piston I , while the inner end of the cap H^2 forms a stop which is encountered by the piston I' ; 30 but the same result can obviously be produced by stops or shoulders otherwise formed or located on the valve-casing and shaft I^2 or elsewhere on the movable or stationary parts of the valve.

40 In Fig. 3 I have shown a modified form of construction embodying my invention, which is employed to prevent the piston from too suddenly closing the water-passage. In said figure the chambers H and H' are constructed with bushings h^6 h^6 , within which the pistons I and I' closely fit. A small water-passage h^7 is formed in the wall of each of the said chambers and leads from the rear portion thereof to the interior of the valve-casing. It 45 will be clearly seen that when either of the pistons enters its chamber it will confine the water therein, which can only escape slowly through one of the small water-passages h^7 , and thus retard the movement of the other piston in closing the main water-passage 50 through the valve-casing. The main purpose of this last-described feature of construction is to prevent the cab from being stopped so suddenly as to bring an undue or 55 dangerous strain on the elevator mechanism. The valve is opened after being automatically closed by reversing the direction in which the water flows through the casing G , it being entirely obvious that the pressure of water on 60 the inner face of the piston which stands in and closes the valve-seat will move both pis-

tons backwardly until they resume the position originally occupied by them.

One important advantage of the safety-valve constructed as herein described is that 70 after it has been automatically actuated to stop the elevator it may be opened from the elevator-cab by simply moving the main valve in the usual manner to reverse the direction of movement of the cab. 75

I claim as my invention—

1. The combination, with the hydraulic cylinder of a hydraulic elevator, of a safety-valve mechanism comprising a valve located in the passage through which the water passes to 80 and from the said hydraulic cylinder and having a movable valve-piston sustained normally out of the direct passage for water, and actuating devices connected with one of the moving parts of the elevator mechanism constructed to strike a part connected with said pistons and to move the latter through a distance less than the distance or "throw" required to fully close the valve when the elevator is near the extreme limit of its movement, and thereby shift the said valve-piston 85 into the said water-passage, while leaving the piston free to be moved by the action of the water. 90

2. The herein-described safety-valve mechanism for hydraulic elevators, comprising a valve-casing located in the water-passage of the hydraulic cylinder and provided with a central valve-seat, two longitudinally-sliding pistons arranged in said valve-casing and 100 held normally at opposite sides of the central valve-seat and out of the direct water-passage, and actuating devices connected with a moving part of the elevator mechanism and adapted to strike a part connected with said 105 pistons and to move one of said pistons toward said valve-seat and into the water-passage when the elevator is near the limit of its movement in either direction, while leaving the piston free to be subsequently moved by 110 the action of the water, substantially as described.

3. The herein-described safety-valve mechanism for hydraulic elevators, comprising a valve-casing located in the water-passage of 115 the hydraulic cylinder and two pistons therein, said valve casing being provided with a valve-seat and two chambers to receive said pistons, a longitudinally-sliding piston-rod supporting said pistons and having one end 120 projecting outside of the valve-casing, and actuating devices connected with a moving part of the elevator mechanism and constructed to strike the said piston-rod and to move one of said pistons toward the said 125 valve-seat through a space less than the stroke of the valve when the elevator is near the limit of its movement in either direction, while leaving the piston free to be subsequently moved by the action of the water, 130 substantially as described.

4. The herein-described safety-valve mech-

anism for hydraulic elevators, comprising a valve-casing located in the water-passage of the hydraulic cylinder and two pistons in said casing, said casing being provided with 5 a valve-seat and with two chambers to receive the pistons, passages for water leading from said chambers to points without the same, said pistons being fitted to the walls of the chambers, and actuating devices connected with said pistons and with a moving part of the elevator mechanism and adapted to move one of said pistons out of its chamber and toward the valve-seat and the other piston from the valve-seat and into its chamber 10 when the elevator reaches the limit of its movement in either direction, substantially as described.

5. The herein-described safety-valve mechanism for hydraulic elevators, comprising a valve-casing located in the water-passage of the hydraulic cylinder and two pistons there- 15

in, said valve-casing being provided with a valve-seat and two chambers to receive said pistons, a longitudinally-sliding piston-rod supporting said pistons and having one end 25 projecting outside of the valve casing, a vibrating lever pivoted to said piston-rod, and two projections or lugs attached to a moving part of the elevator and which are adapted to strike and actuate said lever to move one 30 of said pistons toward the valve-seat through a space less than the stroke of the valve when the elevator is near the limit of its movement in either direction, substantially as described.

In testimony that I claim the foregoing as 35 my invention I affix my signature in presence of two witnesses.
